HYDROPHONE CASING

Russell I. Mason, New London, John F. Ripken, Waterford, and Hector F. Bernier, Jr., Danielson, Conn., assignors to the United States of America as represented by the Secretary of the Navy

Application May 11, 1944, Serial No. 535,170

6 Claims. (Cl. 340—8)

1

This invention relates to underwater signalling apparatus and in particular to the construction and mounting arrangement of the hydrophone casing and suspension cable which form part of the complete radio-sonic buoy described in application, Serial No. 555,154, filed September 21, 1944.

This hydrophone within its casing, when in use, hangs below the buoy in "listening" position. Prior to being placed in service, the hydrophone, its casing and suspension cable are stowed in the bottom compartment of the buoy. However, when the buoy, which is launched by parachute, strikes the water, an impact operated release mechanism, the details of which form no part of the instant invention, functions to permit the hydrophone and its enclosing casing to drop out of the bottom compartment of the buoy and hang by the suspension cable.

A primary object of this invention is to provide a new and improved means for stowing the hydrophone suspension cable in a compact manner within the buoy and in such a way that the cable will pay out easily and without kinking when the hydrophone is released from the buoy.

Another object is to provide a new and improved means for holding the hydrophone casing firmly within the buoy prior to release therefrom.

Other objects and advantages of applicants' novel construction will become apparent from the detailed description to follow and from the accompanying drawings which illustrate preferred embodiments of the invention.

In the drawings,

Fig. 1 is a view partly in elevation and partly in section, of the hydrophone casing and suspension cable, as stowed in the bottom compartment of the buoy, here shown in section;

Fig. 2 is a view in elevation of the hydrophone casing when hung from the buoy in operating position by the suspension cable;

Fig. 3 is a vertical sectional view taken on lines 3—3 of Fig. 2 of the upper end of the hydrophone casing illustrating a preferred construction therefor;

Fig. 4 is an enlarged sectional view of the arrangement shown in Fig. 3;

Fig. 5 is a vertical sectional view taken on lines 5—5 of Fig. 2 showing an alternate construction for the upper end of the hydrophone casing; and

Fig. 6 is a vertical sectional view taken along lines 6—6 of Fig. 2 of the lower cap of the hydrophone casing illustrating the ballast arrangement utilized.

Referring now to the drawings, the lower end of the buoy chamber is shown at 10 and together

2

with a bulkhead 12, tacked or otherwise secured to the buoy casing, and frame 14 of the hydrophone release mechanism 24, comprises a compartment 16 within which are stowed a casing 18 of sound transparent material such as thin metallic sheathing enclosing the hydrophone 11 and suspension cable 20. These are held resiliently in place by a spring 22 of the impact operated release mechanism 24.

The upper end of the cable 20 is secured to the buoy casing by threading it upwardly through a hole 12a in the bulkhead 12 and thereupon knotting it at 12b so as to prevent pulling back.

The construction of the hydrophone 11 per se forms no part of the present invention and has therefore been shown only generally in Figs. 3 and 5. One suitable type of hydrophone having a shell 13 of magnetostrictive material is described in application Serial No. 518,447, filed January 15, 1944, now Pat. No. 2,472,388, by Albert L. Thuras. However, it is to be understood that other types of hydrophone structure such as the piezoelectric crystal type may be used equally as well within the casing 18.

A tube or tubular neck portion 26 having oppositely disposed slots 28 is secured to a top member or closure cap 30 of the hydrophone casing 18 and may be conveniently referred to as the neck portion of the casing. The tube securing means may be as shown in Figs. 3 and 5 to be later described, or tube 26 may be made as a part of the top cap member 30. The cable 20 leading out of the hydrophone is brought out through one of the slots 28 and then wound in several layers upon the tube 26 which thus provides the support for the resulting coil, the diameter of the outermost layer preferably being substantially equal to the outer diameter of the casing 18. Slots 28 provide clearance for cable 20 when the end of tube 26 is brought into contact with the bulkhead 12.

Sidewise motion of the hydrophone casing 18 while stored in compartment 16 is prevented in part by a boss 31 centrally located on the under surface of bulkhead 12 over which the upper end 45 of tube 26 can fit, and in part by a rounded boss 32 formed on a lower cap member 34 which fits into the open conforming end of coil spring 22.

Reference is now made to Figs. 3 and 4 which illustrate one arrangement for securing the lower end of cable 20 inside the hydrophone casing and the tube to the casing cap, forming a watertight seal or coupling to prevent water from getting inside of casing 18. A shouldered bushing 36 is secured to the cap 30a of the hydrophone casing. Tube 26, in turn, is secured to bushing 36.

Through bushing 36 is a hole 38 which may be flared on its inner end. The diameter of hole 38 should be slightly less than the outside diameter of cable 20a.

In this modification, cable 20a consists of a center conductor 40, an insulating sheath 42 of rubber, a concentric sheath 44 of conducting material to serve as a second conductor, and an outer elastic insulating sheath 46 of rubber, shown turned back upon itself. Cable 20a is inserted in the undersized hole 38 for guidance to the interior of the casing 18 in the following manner:

The outer sheath 46 is turned back upon itself for a length of several inches, and the inner and outer conductors 40 and 44 and inner insulation sheath 42 are cut off. The outer sheath 46 is now turned right side out again and the empty portion put through the hole 38 in bushing 36. Tension is now applied to the sheath 46 causing it to stretch and slide over the surface of the outer conductor 44. As sheath 46 stretches, its thickness, and hence the diameter of cable 20a is reduced until the cable will pass through the hole 38. After the cable has thus been pulled through the hole 38, tension upon the sheath 46 is relieved whereupon the latter will snap back, expand and jam itself in the hole 38, thereby forming both a good mechanical clamp on cable 20a and a waterproof seal.

As an additional measure of security, the outer sheath 46 may again be rolled back upon itself as shown in Fig. 4 and a wrapping of a few turns of wire 48 soldered to the outer conductor 44. When sheath 46 is then again turned right side out to cover the wire wrapping 48, a jamming device is formed which will function in the event of failure of the securing means previously described. If such securing means fails, the cable 20a will be pulled through the hole 38 until the bulge caused by the wrapping 48 seats itself in the flared end of hole 38.

An alternate embodiment for securing the cable within casing 18 is shown in Fig. 5 to which reference is now made. In this particular embodiment, the upper cap 30b of casing 18 is provided with a boss 50 upon which the tube 26 is soldered or otherwise fixedly secured. Cable 20b is passed through an opening in the center of boss 50 and then tied in a knot 52 on the underside which prevents it from being pulled out. The cavity formed by this boss provides a suitable recess for the knot. Waterproofing is obtained by partially filling the inside of tube 26 with any well-known sealing compound 54.

In order to make the hydrophone casing 18 hang vertically, the lower cap member 34 may be filled with molten lead 56 as shown in Fig. 6. A small hole 58 through the cap and lead permits the hydrophone casing 18 to be tested with air pressure for leaks after which the hole 58 may be closed by solder.

Operation

When the buoy is launched by parachute, it floats down, the bottom end striking the water and causing the impact operated release mechanism 24 to function whereupon the hydrophone 11 and its enclosing casing 18 drops out of the bottom compartment 16 of the buoy. As casing 18 descends into the water, the coil of cable 20 will pay out layer by layer evenly and without kinking and will finally become taut as shown in Fig. 2.

In conclusion it is to be understood that while the constructions shown and described are preferred embodiments of the invention, it will be

evident that changes may be made therein by those skilled in the art without departing from the spirit and scope of the invention as defined in the appended claims.

Having thus fully described our invention, we claim:

1. A fluid tight casing releasably carried within a chamber immersible in a fluid medium, said casing having a closure cap, a suspension cable in said chamber having one end secured to a portion of the chamber, a tube upstanding from the casing providing means on which the cable is coiled, means projecting from the cap by which the tube is affixed to the cap and through which the other end of the cable is guided to the interior of the casing, and elastic means tight around the cable and compressibly engaging in the projecting means to make a fluid tight coupling between the projecting means and said cable.

2. In a fluid tight casing releasably carried within a chamber immersible in a fluid medium, a cable emerging from the casing and secured at its end remote from the casing to a portion of the chamber, and a fluid seal for the cable consisting of a bushing having a hole through which the cable emerges, and an elastic sheath on the cable compressibly occupying the hole.

3. In a fluid tight casing releasably carried within a chamber immersible in a fluid medium, a cable emerging from the casing and secured at its end remote from the casing to a portion of the chamber, and a fluid seal for the cable consisting of a boss on the casing having a hole through which the cable emerges, a tube fixed on the boss around part of the cable, and sealing compound in the tube and on the boss around said cable closing the hole.

4. Apparatus of the character described comprising a container having a hollow base member and a smaller upper member extending upward from the said base member, said upper member having an open vertical passageway therein communicating with the inside of said hollow base member, a cable extending from within said base member through said passageway and emerging through the open end thereof, the outer portion of said cable including a resilient material having an outer diameter which is normally greater than the adjacent portion of said passageway, said resilient cable portion being held in a stretched condition by the adjacent walls of said passageway whereby a fluid-tight joint is formed.

5. A fluid-tight joint in a system including a hollow member which is to be completely immersed in a fluid and a cable which is to extend between the inside and outside of said hollow member comprising a hollow member, an opening in said hollow member, a cable extending through said opening, the outer portion of said cable including a resilient material having an outer diameter which is normally greater than the adjacent portion of said opening, the said outer resilient portion of said cable being held in a stretched condition by the walls of said opening whereby a fluid-tight joint results.

6. Apparatus of the character described comprising a container having a base portion and an upper portion extending upwardly from the top of said base portion, said upper portion including an open vertical passageway in the central portion thereof which communicates with the inside of the base portion of said container, said upper portion also including a pair of oppositely disposed vertical slots in the sides there-

of extending downward from the open end of said passageway, a storage chamber, said container releasably disposed within said storage chamber, resilient means compressing said container against the upper portion of said chamber with the open end of said passageway in said upper portion of said container enclosed by the upper portion of said chamber, a cable wound about the said upper portion of said container with one end thereof extending through both of said slots and connecting to the said chamber from within said passageway, the other end of said cable extending through one of said slots and communicating with the inside of said lower portion of the said container, means providing a fluid seal between said cable and the walls of said passageway adjacent thereto, means fixedly anchoring said other end of said cable to said con-

5 tainer, means anchoring the said one end of said cable to said chamber.
